(57) **CLAIM**

I claim the ornamental design for a snack chip eating utensil, as shown and described.

DESCRIPTION

FIG. 1 is a side elevation, front and top perspective view of the snack chip eating utensil;

FIG. 2 is a top plan view of the snack chip eating utensil;

FIG. 3 is a rear view of the snack chip eating utensil;

FIG. 4 is a side elevation view of the snack chip eating utensil;

FIG. 5 is a front view of the snack chip eating utensil; and,

FIG. 6 is a bottom view of the snack chip eating utensil.

The broken line showing of environment in FIG. 1 is included for the purpose of illustration only and forms no part of the claimed design.
